UNITED STATES PATENT OFFICE

GEORGE D. COLLINS, OF HOUSTON, TEXAS

PUMP

Application filed July 14, 1927. Serial No. 205,752.

This invention relates to new and useful improvements in a pump.

One object of the invention is to provide a pump embodying a casing having an intake and a discharge with a novel type of impeller blade in the casing and novel means for rotating the blade to effect the intake and discharge of the fluid being pumped.

Another object of the invention is to provide, in a pump, a novel type of packing between said blade and the casing wall.

A further feature of the invention is to provide, in a pump, a valve controlled bypass from the high pressure side of the casing chamber to the low pressure side of said chamber.

A still further feature of the invention is to provide, in a pump of the character described a driving eccentric in contact with the wall of the casing chamber, between the intake and discharge openings, with means for adjusting said eccentric to maintain a close joint between it and said wall.

With the above and other objects in view this invention has particular relation to certain novel features of construction, operation and arrangement of parts, an example of which is given in this specification and illustrated in the accompanying drawings, where-

in:

Figure 1 shows an end view of the pump, shown partly in section and with the end plate removed.

Figure 2 shows a vertical sectional view of the pump taken on the line 2—2 of Figure 1.

Figure 3 shows a side view of the impeller blade.

Figure 4 shows an inside view of the removable end plate of the pump casing.

Figure 5 shows a sectional view thereof, taken on the line 5—5 of Figure 4, and

Figure 6 shows a sectional view thereof taken on the line 6—6 of Figure 5.

Referring now more particularly to the drawings, wherein like numerals of reference designate similar parts in each of the figures, the numeral 1 designates a pump casing as a whole which has one of its end plates, as 2, removable and whose other end plate

is formed with an extended tubular bearing 3 which carries a stuffing box 4. The pump casing has the intake line 4 and the discharge line 5 entering the pressure chamber 6 in the casing. Within said chamber there is an eccentric 7 preferably cup shaped in form and this eccentric is fixed to the inner end of the drive shaft 8 which works through said stuffing box and which has the eccentric sleeve 9 around it which forms a lining for the bearing 3. The eccentric 7 works in frictional contact with the wall of the chamber 6 between the intake line 4 and the discharge line 5, said pressure chamber between the eccentric and the inner wall of the casing thus being crescent shaped. The rim 10 of the eccentric 7 has the oppositely disposed notches 11, 11, and there is an impeller blade 12 extending transversely of the eccentric and which is seated in said notches, the outer ends of said impeller blade being widened as at 13 so as to extend entirely across the chamber 6 from end plate to end plate of the casing and notches 11 are of sufficient depth to permit a relative radial movement 75 of the blade and eccentric as the eccentric is rotated. This impeller blade has a central transversely elongated bearing 14 and there is a bearing pin 15 mounted in a suitable bearing 16 in the end plate 2 with its inner 80 end 16' projecting into said bearing 14, said inner end 16' being enlarged, as shown in Figures 1 and 2 and concentric with respect to the chamber 6. The outer ends of the impeller blade 12 have the deep grooves 17, 17, 85 cut across said ends with suitable packing strips 18, 18, seated therein. There is an arcuate spring 19 whose ends 20 are outwardly turned and work through the bearings 21, 21 in said blade with their outer 90 ends resting against the inner sides of the packing strips 18 and holding the packing 95 yielding against the inner wall of the chamber 6.

As the eccentric 7 is rotated the impeller blade will sweep around the wall of the chamber 6 and will induce the flow of the fluid being pumped through the inlet pipe 4 into the chamber 6 behind the impeller blade and will force the fluid in said chamber in front 100

of the impeller blade out through the discharge pipe 5. The sleeve 9, as hereinbefore stated, is eccentric with relation to the shaft 8 and is held in fixed relation in the bearing 3 by means of a set screw 22. In case the periphery 5 of the eccentric or contacting portion of the wall of the chamber 6 should become worn so as to permit leakage through the joint between them the set screw 22 may be loosened 10 and the sleeve 9 adjusted so as to cause a closer fit between the worn parts and the set screw 22, then tightened to secure the sleeve 9 in such position of adjustment.

It is to be noted that the shaft 8 may be 15 rotated in either direction. If rotated in one direction the pipe 4 will serve as an inlet pipe and the pipe 5 as a discharge pipe but if rotated in the other direction the pipe 5 will serve as an inlet pipe and the pipe 4 as a discharge 20 pipe.

The chamber 6 is, in effect, separated by the impeller blade 12 into a high pressure chamber in front of one end of the impeller blade and a low pressure chamber behind the 25 other end of the impeller blade.

The removable end plate 2 is formed with two valve casings 23, 24, and has the relief conduits 25, 26, therethrough which lead through the respective valve casings 23, 24, 30 from the high pressure chamber, as above described to the low pressure chamber. These valve casings 23, 24, are closed by the outer end caps 27, 28 and located in said casings are the relief valves as 29 which work against 35 and are normally held closed by the pressure springs 30. In case the discharge line 4, or 5 as the case may be, should for any reason become clogged or blocked so as to cause an excessive pressure in the high pressure chamber the corresponding valve 29 will be lifted 40 to permit the return of the fluid through the corresponding conduit 25 or 26, as the case may be, to the low pressure side of the chamber. The springs 30 are of sufficient strength 45 to hold the valves 29 closed during the normal operation of the pump, to block the corresponding relief conduit.

What I claim is:—

1. A pump including a casing having an 50 internal chamber provided with an inlet and a discharge outlet, a rotatable driving member in said chamber and in contact with the chamber wall between said inlet and outlet, a transverse impeller blade spanning said 55 chamber and operatively connected with and driven by said driving member, packing elements carried by the blade ends, and a single yieldable member against the respective ends of which the respective packing elements are 60 mounted, and which is effective to hold said elements yieldingly against the walls of said chamber and means for adjusting said driving member relative to the chamber wall.

2. A pump including a casing having an 65 internal chamber provided with an inlet and

an outlet, a rotatable driving member in said chamber, said member being eccentric with respect to said chamber and having its periphery in contact with the chamber wall between said inlet and outlet, a drive shaft 70 fixed to said driving member, a bearing in the casing, a sleeve in said bearing having an eccentric bearing in which said shaft rotates, said sleeve being adjustable to vary the position of the driving member in said chamber, 75 an impeller blade spanning said chamber whose ends are disposed to sweep around the chamber wall, said blade being operatively connected with said driving member, packing carried by each end of said blade, and a 80 single yieldable member whose respective ends work against said packing to hold the same against the casing wall.

3. A pump including a casing having an 85 internal chamber provided with an inlet and an outlet, a rotatable driving member in said chamber, said member being eccentric with respect to said chamber and having its periphery in contact with the chamber wall between 90 said inlet and outlet, a driving shaft fixed to said driving member, a bearing in the casing, a sleeve in said bearing having an eccentric bearing in which said shaft rotates, said sleeve being adjustable to vary the position of the driving member in said chamber, an 95 impeller blade spanning said chamber whose ends are disposed to sweep around the chamber wall, packing carried by said ends, an arcuate spring whose ends are outwardly turned and work in bearings in said blade 100 against said packing, said blade being operatively connected with said driving member, a bearing member carried by the casing substantially concentric with the chamber thereof, said impeller blade having a bearing on 105 said bearing member.

In testimony whereof I have signed my name to this specification.

GEORGE D. COLLINS.
